UNITED STATES PATENT OFFICE.

HARRY E. KERR, OF CLEVELAND, OHIO, ASSIGNOR TO THE CLEVELAND GAS BURNER & APPLIANCE COMPANY, OF CLEVELAND, OHIO, A CORPORATION OF OHIO.

GAS BURNER.

Application filed September 9, 1926. Serial No. 134,390.

The present invention pertains to an improvement in gas burners of the general type shown and described in my Letters Patent of the United States, dated Nov. 3, 5 1925, No. 1,560,248. Thus the improved burner embodies air and gas delivery tubes corresponding to the tubes in the patented burner and arranged in reversely-inclined relation to bring separate streams of combustible mixture into confluence and to generate a spreading column of flame apart from the mouth of each tube and the body of the burner. The present burner is distinguished however from the patented burner in that 10 the burner body is particularly constructed to provide a double row of delivery tubes at different elevations and projected toward each other at right angles to produce a sheet or column of flame in an oblique or slanting plane so that it may be directed against a vertical wall such as a fire pot wall in a boiler, furnace or other heating apparatus. In addition, the present burner considered as a whole comprises a plurality of sections 15 or units, adapted to form a large ring-shaped burner when assembled, each section or unit having a valved connection leading to a common source of gas supply, and each section or unit comprising two hollow circular segments concentrically arranged in different horizontal planes and having co-operating 20 pairs of tubes mounted radially thereon.

In the accompanying drawings, Fig. 1 is a sectional view of my improved burner, 25 mounted within the fire pot of a circular furnace or boiler. Fig. 2 is a perspective view of the complete burner connected to a gas supply header. Fig. 3 is a perspective view of one of the burner sections or units. Fig. 40 4 is a sectional view of one of the burner sections on the line of a pair of co-operating jets or delivery tubes.

In Fig. 1 I show my improved burner A mounted upon a grate 2 within a boiler or furnace 3, the showing of this particular boiler being merely an exemplification of one adaptation of the burner to a known structure embodying a fire pot 4. To obtain the full benefit of the heat generated by a gas

burner in a boiler or furnace of this general type it is especially desirable that the mixed gases and flames from the burner be projected against the walls of the fire pot and that combustion takes place at the sides and over the entire area or full height thereof instead of being produced merely within the central area of the fire pot. The present burner is therefore particularly constructed to direct the combustible gases obliquely in an upward direction against the fire pot wall, and 55 comprises a plural number of sections or units —a—, arranged within the fire pot closely adjacent the inner wall thereof. In the present instance three units —a— are assembled together each being a segmental 60 part of a double ring to permit a circular gas burner to be formed thereby which is nearly as large at its greatest diameter as the inner circular wall of the fire pot, and this sectional construction is desirable and 65 of great advantage because it permits the burner to be assembled, section by section, within boilers having grates for burning hard fuel and in which the fire pot doors or entrances are of much smaller size than the 70 fire chamber. Moreover, each unit —a— is provided with a separate pipe connection 5 leading to a gas supply manifold or header 6, and separate valves 7 are used to control the supply and operation of each unit, so 75 that one or more or all the units may be operated at will or as heating conditions may require.

The burner units —a— are constructed alike, so that a description of one will suffice 85 for all. Thus, each unit comprises two hollow circular parts or segments 8 and 9, respectively, of different diameter, which segments are concentrically arranged and united together at their middle by a tubular connection 10. The opposite ends of each segmental part are closed or plugged and the corresponding ends are connected together by solid tie bars or webs 11. Outer segment 8 is relatively longer than the inner segment 9, and these two segments, as united together 90 by middle connection 10 and the end tie bars 11, form a separable sector of a complete

ring-shaped burner A which may be used advantageously within a round fire pot. Connecting tube 10 and tie bars 11 extend inwardly and upwardly on slanting lines from outer segment 8 to support inner segment 9 at a higher elevation than outer section 8. The two concentric segments are thus supported parallel with each other but in different horizontal planes, and supply pipe 5 is connected to a boss 12 depending from one of the segments at about the middle thereof, and preferably from the inner segment 9 opposite the end of connecting tube 10 for convenience in making header connections and to permit all of the connecting pipes 5 to pass through a single opening in the side wall of the furnace beneath the burner.

A series of small bosses 14 are formed oppositely at spaced intervals upon the segment 8 and 9, and a series of gas delivery jets, tubes or nozzles 15 are screwed into these bosses in open communication with the hollow gas-distributing passage 16 in each segment, the tubes being arranged in pairs and the tubes of each pair being projected toward each other at approximately right angles so that two separate streams of gas will be discharged and brought together opposite and apart from the outer ends of the tubes. Thus each tube has a small gas orifice 17 in its base and one or more lateral air intake openings 18 in its side closely adjacent said orifice, whereby a fine stream of gas will be discharged into and through the tube and a predetermined amount of air will be entrained and discharged with the gas. Under maximum operating pressures the two gas streams are brought into confluence and deflected at a diverging angle to the axis of each tube and no combustion takes place at or in the zone of meeting of the two gas streams except when the flow of gas is at reduced pressure. Normally a spreading column of flame is generated some distance apart from each pair of co-operating tubes and by mounting two sets of such co-operating tubes at right angles and also at different elevations, the combustible mixture and columns of flame will be projected obliquely or on upwardly slanting lines from each burner unit —a— and at spaced intervals around each unit against the lower part of the fire pot and upwardly along its sides with highly efficient heating results. In a circular burner the separate sheets and columns of flame strike the fire pot radially thereof but in such close proximity that a continuous circular sheet of flame is produced within the fire pot. However, if only a sector of the fire pot is to be heated, the flow of gas to one or more units may be cut off at the valves 7, and the volume or height of the flame at each unit may also be independently controlled by such valves.

What I claim, is:

1. A gas burner, comprising concentric hollow gas distributing rings of different diameters lying in different horizontal planes, having separate rows of gas delivery tubes extending therefrom and projecting toward each other in pairs to deliver separate streams of combustible mixtures into confluence with oblique deflecting effect relatively to the said horizontal planes. 75

2. A gas burner, comprising a pair of hollow gas distributing rings of different diameters supported at different elevations, a series of air and gas delivery tubes extending horizontally from the smaller and higher ring, and a series of air and gas delivery tubes extending vertically from the larger and lower ring, the said tubes being arranged oppositely in pairs to deliver separate streams of combustible mixtures into confluence with oblique deflecting effect. 80

3. A gas burner, comprising a hollow gas distributing body having air and gas delivery tubes extending horizontally therefrom and air and gas delivery tubes extending vertically therefrom, the said horizontal and vertical tubes being arranged in pairs to deliver separate streams of combustible mixtures into confluence and to spread the confluent mixtures in an oblique plane. 90

4. A gas burner, comprising a plurality of segmental units, each unit having a row of horizontally extending air and gas delivery tubes and a row of vertically-extending air and gas delivery tubes, the respective tubes in each row being projected toward companion tubes in the other row to deliver separate streams of combustible mixtures into confluence and to spread the confluent mixtures in an oblique plane. 100

5. A gas burner, comprising hollow circular segments lying in different horizontal planes having air and gas delivery tubes extending toward each other at substantially right angles therefrom, said angularly related tubes being arranged in pairs adapted to bring two separate streams of combustible mixture into confluence with spreading effect obliquely to the said horizontal planes. 110

6. A gas burner, comprising a set of segmental gas-distributing units, said units when assembled forming two concentric rings at different elevations, and each unit having air and gas delivery tubes extending from their ring portions and projected toward each other at substantially right angles. 115

7. A gas burner, comprising a pair of hollow rings of different diameters having tubular connections supporting one ring in a higher plane than the other ring, and said rings having air and gas delivery tubes extending radially therefrom toward each other at substantially right angles. 125

8. A gas burner, comprising a pair of

circular gas distributing segments lying in different horizontal planes and having a connecting tube, one of said segments having upwardly-extending air and gas delivery tubes and the other segment having laterally-extending air and gas delivery tubes, said tubes being arranged in pairs, and each 5 pair of tubes being projected toward each other at substantially right angles to bring two streams of combustible mixture into 10 confluence with oblique spreading effect at one side of the burner.

In testimony whereof I affix my signature.

HARRY E. KERR.
